UNITED STATES PATENT OFFICE.

CHRISTIAN PEDERSEN, OF ST. LOUIS, MISSOURI, ASSIGNOR TO LANDIS MACHINE COMPANY, OF ST. LOUIS, MISSOURI, A CORPORATION OF MISSOURI.

THREAD-LAYING DEVICE.

No. 813,822.

Specification of Letters Patent.

Patented Feb. 27, 1906.

Application filed August 14, 1905. Serial No. 274,114.

To all whom it may concern:

Be it known that I, CHRISTIAN PEDERSEN, a citizen of the United States, residing at St. Louis, Missouri, have invented a certain new and useful Improvement in Thread-Laying Devices, of which the following is a full, clear, and exact description, such as will enable others skilled in the art to which it appertains to make and use the same, reference being had to the accompanying drawings, forming part of this specification, in which—

Figure 1 is a side elevational view of a portion of a sewing-machine provided with a thread-laying mechanism constructed in accordance with my invention. Fig. 2 is a fragmentary top plan view of the thread-laying mechanism. Fig. 3 is a plan view of the cam-groove and illustrated in diagram. Fig. 4 is a cross sectional view on the line 4-4 of Fig. 2. Figs. 5 and 6 are diagrammatical views showing the relative positions of the loop-forming elements at their extreme position. Fig. 7 is a detailed perspective view showing the relative positions of the loop-forming elements at the starting position of the needle, and Fig. 8 is a similar view showing the relative positions of the two elements after the stitch has been formed.

This invention relates to machines for sewing leather; and one of the objects is to provide a sewing-machine having a novel form of thread-laying mechanism whereby the stitch may be conveniently and expeditiously made during the operation of the machine.

Other objects and advantages, as well as the novel details of construction, will be specifically set forth in the following description, it being understood that changes in form, proportion, and minor details of construction may be resorted to without departing from the spirit of this invention or sacrificing any of the advantages thereof.

In order to appreciate the novel features of this invention, reference should be had to the accompanying drawings, particularly to Fig. 1, in which 1 designates a shaft driven by appropriate means and carrying a disk having cams 3 and 4, the cam 3 being approximately concentric with the shaft on one side of the line marked $x\ x$ and eccentric on the opposite side of said line. The cam 4 is concentric with the shaft on one side of the line marked $y\ y$ and eccentric to the shaft on the opposite side of the line. Appropriately positioned on the machine-frame is a journal 5. This

journal supports the operating-levers for the two thread-laying elements to be referred to hereinafter. The lever designated by the reference-numeral 6 is what I term the "looper-actuating element," while the lever 7 designated by the numeral 7 is the "hook-actuating element." This lever 6 is constricted at its upper end, as indicated at 8, and the constricted portion of said lever 6 loosely fits in an elongated recess in a slide 9, 65 guided at its upper extremity in a slot in the bracket 11. The loop-forming element which is connected to slide 9 consists of an approximately horizontal bar slidably secured in a guideway 12, the forward end of said bar being curved and provided with an eye or thread-opening 13. The rear end of said bar is provided with a laterally-projecting portion 14, connected to a rearwardly-exposed extension 15, which is secured to the slide 9 by suitable fastening device. The looper element has what might properly be termed an "oscillatory" movement—that is to say, it not only moves in a reciprocatory manner, but also has a sidewise or lateral movement 80 in a horizontal plane, as will be apparent as the construction and operation of the invention are better understood. Intermediate the ends of the looper is an elongated slot 16, in which is adjustably secured an extension 17 85 on the side of the vibrating lever 18, which assists the lever 6 in imparting the oscillatory movement to said looper. On the end of said lever 18 is a depending roller 19, which is movable in a cam-groove 20 in the periphery of the disk 2. In order to explain the operation of this lever 18, I have illustrated the cam in diagram in Fig. 3. Said peripheral cam consists of a straight groove from a to b , thence an offset portion from b to c , which portion is offset from left to right. Beyond the portion indicated from b to c is another offset portion from c to d , which is offset from right to left, the remaining portion of the cam from d to a being approximately the same as from a to b . The hook member comprises a reciprocating bar 21, which is slidably in a bearing secured to the frame and which is connected at its rear end to the lever 7, which lever 7 is provided intermediate its ends with a roller 22, working in cam 3, the hook-shaped end of the bar 21 being located at the rear of the eye of the looper. The lever 6 is provided with a roller 23, working in the cam 4. As the needle-operating mechanism cooperates with the 110

thread-laying mechanism in producing the stitch, I will describe such part thereof as may be necessary to a proper understanding of the invention.

5 An operating-lever 23^a is adapted to be operated by some suitable means to vertically reciprocate the needle-bar 24, which needle-bar will impart the necessary rocking movement to the needle-carrier 25, so as to actuate the needle 26 and cause it to pass through the work and through the work-table 27 adjacent to the thread-laying mechanism.

28 designates the take-up lever, the appropriate mechanism associated therewith forming the subject-matter of a separate application, Serial No. 274,113, filed August 14, 1905.

All the parts being assembled, the operation will be as follows: Assuming the parts to 20 be in the position shown in Fig. 1 and the thread-laying elements to be in the position shown in Fig. 5, the rotary movement of the shaft 1 will cause the cams 3 and 4 to actuate the levers 6 and 7 for moving the looper and 25 the hook rearwardly. The cam 4 is so shaped that at approximately the commencement of the cycle of operations a greater degree of movement will be imparted to the lever 6 than to the lever 7, thereby causing the 30 looper to be moved slightly to the rear of the hook on the bar 21. The portion *b* to *c* of the cam-groove 20 will then actuate the lever 18 for imparting a slight lateral movement to the looper, and immediately thereafter a 35 depressed portion in the cam 4 will actuate the lever 6 for imparting a slight forward movement to the looper for causing it to carry the thread into engagement with the hook. The portion from *c* to *d* of the cam-groove 20 will then actuate the lever 18 for 40 imparting a lateral movement in the opposite direction to the looper, which is thereafter moved rearwardly to lay the thread onto the barb of the needle, as shown in Fig. 7. The 45 needle then moves upwardly to draw the loop of thread through the work, and the continued rotation of the cams 3 and 4 moves the hook forwardly to carry it out of engagement with the thread and also moves the 50 looper laterally and forwardly back to normal position, as shown in Fig. 8. In Figs. 5 and 6 the broken lines indicate the path of movement of the looper. By adjusting the 55 fastening device on the projection 17 the proper degree of movement of the looper may be governed.

Of course it is to be understood that the take-up device 28 and the other accessories necessary to the successful operation of a 60 sewing-machine will be employed; but it is not deemed necessary to herein refer to the details of construction of said mechanism.

Having thus described the invention, what is claimed as new, and desired to be secured 65 by Letters Patent, is—

1. In a thread-laying mechanism for sewing-machines, the combination of an oscillatory lever having a thread-eye at one end; a horizontal movable lever pivoted to the frame of the machine and connected to said 70 first-mentioned lever, a cam for actuating said second-mentioned lever, a rocking lever connected to the frame and to the first-mentioned lever, a cam for actuating the third-mentioned lever and a sliding hooked element 75 coöperating with the first-mentioned lever to lay the thread about the barb of the needle, substantially as described.

2. In a thread-laying mechanism for sewing-machines, an oscillatory thread-carrying lever, a pivoted element engaging said lever, a cam in engagement with said pivoted element and having a relatively straight groove, an offset groove the wall of which is offset slightly beyond the side wall of the 85 straight groove and another offset groove the wall of which is offset slightly beyond the opposite side of said groove, and means for imparting a movement to said lever, at an angle to the movement imparted by the pivoted element and a reciprocatory hooked element for engagement with the thread and coöperating with the thread-carrying lever, substantially as described.

3. In a thread-laying mechanism for sewing-machines, the combination with a needle, a mechanism for actuating it, of a thread-laying mechanism for laying the thread about the needle comprising a thread-carrying lever, a pivoted element carried by the machine-frame and connected to said lever, said pivoted element having a movement at an angle to the axis of said lever, means for imparting movement to said lever at an angle to the movement of said pivoted element 100 and a hooked member for engagement with the thread said hooked member having a movement at an angle to the angle of the movement of the pivoted member, substantially as described.

4. In a thread-laying mechanism for sewing-machines, an upstanding pivoted member carried by the machine-frame, a cam for actuating said pivoted member, a slide on the free end of such pivoted member, a support for said slide, a thread-carrying member connected to said slide, a lever engaging said thread-carrying member intermediate its ends, a cam for actuating said pivoted lever and a reciprocatory thread-engaging element 115 coöperating with said thread-carrying element, substantially as described.

In testimony whereof I hereunto affix my signature, in the presence of two witnesses, this 11th day of August, 1905.

CHRISTIAN PEDERSEN.
